UNITED STATES PATENT OFFICE

JOHN C. SCOVEL, JR., OF CHICAGO, ILLINOIS, ASSIGNOR TO THE CREAMERY PACKAGE MFG. COMPANY, OF CHICAGO, ILLINOIS, A CORPORATION OF ILLINOIS

REFRIGERATING APPARATUS

Application filed April 10, 1929. Serial No. 353,917.

The invention relates to the construction of the refrigerating cylinders in ice cream freezers of the type adapted to the employment directly of a low boiling temperature refrigerant, such as ammonia, and which are commonly known as direct expansion freezers.

Such freezers are commonly provided with a pair of endwardly joined spaced concentric cylinders providing an annular boiling or expansion chamber for the refrigerant between the cylinders, of which the inner one is adapted to contain the liquid ice cream mix to be frozen. Heretofore, it has been the practice to provide an opening in the bottom side of the outer cylinder for a pipe connection by which to admit the liquid refrigerant to the expansion chamber, and to provide another single opening in the top side of the outer cylinder for another pipe connection by which to draw off the vaporized refrigerant from the expansion or boiling chamber.

As heretofore constructed, with the single draw-off or suction outlet, the efficiency of evaporation was greatest in a circumferential path directly between the inlet and the outlet, while the boiling action in the refrigerant in the end portions of the expansion chamber became sluggish and less efficient because of the accumulation of the expanded gas or vapor in and above the liquid refrigerant in the end portions remote from the outlet, and which had to be drawn laterally across the chamber for escape through the outlet. The consequences of such conditions are that the refrigerating effect upon the contents of the inner cylinder is much faster at the center portion than at either end portion, and that the slower absorption of heat at the end portions of the freezer materially increases the time period necessary to freeze a batch of ice cream.

It is the object of this invention to provide a cylinder structure for ice cream freezers having an arrangement of plural suction outlets for the vaporizing refrigerant in the expansion chamber so that all portions of the refrigerant therein will boil uniformly, and the refrigerating effect upon the ice cream

mix will be uniformly at maximum efficiency from end to end of the cylinder. Other objects and advantages will be apparent in the following detailed description of a preferred embodiment of the invention illustrated in 55 the accompanying drawings.

Referring to the drawings, Fig. 1 is a longitudinal sectional view in elevation of an ice cream freezer cylinder embodying the invention, and Fig. 2 is an end view of the 60 same. The other component parts of an ice cream freezer being well known to those familiar with the art, illustration thereof is deemed not necessary herein.

In the drawings, the numeral 1 indicates 65 an inner cylinder about which an outer cylinder 2 is positioned in concentric spaced relation, the adjacent ends of the respective cylinders being joined preferably by filler rings 3 effecting a permanent seal between 70 the cylinders and forming an intermediate annular chamber 4. An opening 5 in the bottom portion of the outer cylinder 2 communicates with a pipe 6 threaded into a coupling 7 preferably welded to the cylinder 75 wall. The pipe 6 serves to conduct liquid refrigerant to the inlet opening 5 and into the expansion or boiling chamber 4.

Upon the top side of the outer cylinder 2 is mounted a longitudinally extending shell 80 having its edges sealed, preferably by welding, to the cylinder wall, and forming a manifold enclosing with the cylinder a suction chamber 9. Spaced longitudinally along that portion of the outer cylinder wall 85 enclosed by the manifold, are a plurality of openings 10 forming outlet passages from the expansion chamber 4 into the suction chamber 9. A main suction outlet opening 11, in the intermediate upper portion of the 90 manifold wall, communicates through a coupling 12, preferably welded to the manifold, with a pipe 13 serving as the suction return for the vaporized refrigerant. An outer jacket 14 may also be provided about 95 the outer cylinder and the manifold with spacing therebetween for heat insulating material 15, the jacket being endwardly supported upon filler rings 16.

By the arrangement herein disclosed, it 100

will be apparent that the vapor forming in the refrigerant, as it boils in the annular chamber 4, may rise directly upward and find an exit into the suction chamber 9 with but slight deflection through one of the outlet passages 10, with uniformity of such action throughout the length of the expansion chamber. The suction chamber 9 and the main suction outlet connection 13 are of sufficient capacity to maintain an equalized suction at each of the passages 10, and uniformly clear the expanding vapor from the expansion chamber, thereby effecting uniform refrigerating capacity or efficiency over the entire length of the inner cylinder 1.

15 I claim as my invention:

1. A pair of spaced cylinders having their ends joined and forming therebetween a refrigerant expansion chamber, one of said cylinders having a refrigerant inlet opening in the bottom portion thereof and having a series of spaced outlet openings in the top portion thereof, and a manifold marginally mounted on said cylinder forming a suction chamber in outward sealed communication with said series of outlet openings, said manifold having a suction outlet opening.
- 20 2. A pair of spaced cylinders endwardly joined to form a refrigerant expansion chamber therebetween, one of said cylinders having a refrigerant inlet opening in the bottom portion thereof and having a series of outlet openings spaced longitudinally in the top portion thereof, and a manifold sealed upon said cylinder in outward spaced enclosure of said series of outlet openings, said manifold having a suction outlet opening.
- 25 3. A pair of spaced cylinders endwardly joined to form a refrigerant expansion chamber therebetween, the outer one of said cylinders having a refrigerant inlet opening through the bottom portion thereof and having a series of spaced outlet openings in longitudinal arrangement through the top portion thereof, and a centrally spaced outer enclosure wall marginally sealed upon said outer cylinder about said outlet openings to form a suction manifold, said wall having a suction outlet therethrough.

In witness whereof I have hereunto affixed my signature.

JOHN C. SCOVEL, JR.
